ATTORNEY.

UNITED STATES PATENT OFFICE.

HAROLD D. CORNWALL, OF LOWVILLE, NEW YORK.

EXTRACTOR-CAP.

1,210,050.

Specification of Letters Patent. Patented Dec. 26, 1916.

Application filed November 1, 1915. Serial No. 59,073.

To all whom it may concern:

Be it known that I, HAROLD D. CORNWALL, a citizen of the United States, and resident of Lowville, in the county of Lewis, in the State of New York, have invented new and useful Improvements in Extractor-Caps, of which the following, taken in connection with the accompanying drawings, is a full, clear, and exact description.

10 This invention relates to certain improvements in extractor caps or closures for bottles, jars, and the like, and is particularly adapted for use with milk bottles.

The primary object of the invention is to improve this type of cap in at least three characteristics:—First, to improve the means provided for gripping the extractor portion of the cap. Second, to render the extractor more efficient in the removal of the cap from the bottle, due to the formation of oppositely extending stitches forming spaced lifting parts preferably positioned on the cap at an eccentric point and adjacent one edge and having gripping portions or handles associated therewith, and normally lying in a chord or base of a segment of the disk so that an inwardly inclined radial pull upon the handles when moved to vertical position produces a lever-

30 age action, exerted at an angle to the plane of the disk and across the longitudinal axis of the stitches and the gripping handles, thereby tending to first displace the adjacent edge of the disk from the bottle in such 35 a manner that it lifts at an angle to its normal plane, thereby permitting the gradual and easy removal, not only of the adjacent edge portion, but of the remaining peripheral portions of the disk. Third, to increase 40 the strength, rigidity and effectiveness of the association of the parts. By connecting the extractor to the disk by two spaced stitches and by exerting a uniform and simultaneous pull upon both stitches, the 45 tendency of either to tilt and bend is neutralized and the efficiency and possible pulling strength of the extractor is increased.

Another essential object relates to the production of an extractor cap that will "stack" perfectly in the tube containers from which they are withdrawn as applied to bottles, by the usual automatic capping machines.

Other objects and advantages will appear from the following description, taken in

connection with the accompanying drawings, in which— 55

Figure 1 is a top plan view of the extractor cap. Fig. 2 is an enlarged cross section on line 2—2, Fig. 1, illustrating the cap as positioned in the neck of a bottle shown in dotted lines. Fig. 3 is an enlarged perspective view of the extractor portion before its application to the cap. 60

Caps of this character usually comprise disks of cardboard suitably treated to prevent deterioration, and are usually made circular to fit snugly in the necks of bottles to effectively close the same against escape of the bottled liquid and against the entrance of dust and other foreign matter. 70

— The extracting device which, together with the disk —1—, forms the subject-matter of the present invention preferably comprises a relatively narrow exceedingly thin strip or wire —2— of suitable material, such as sheet metal, securely applied to the upper surface of the cap and lying in a plane substantially coincident with the upper surface of the disk and wholly within the periphery thereof, and in the figures of the drawing the thickness of the metal is somewhat exaggerated so that the construction and arrangement will clearly appear. 75 80

In accomplishing the objects of this invention, the intermediate portion of the wire —2— is firmly secured to the disk —1— so as to form oppositely extending end portions —3— and —4— adapted to be raised to a vertical position and to form in contact a unitary gripping portion or handle, clearly shown in dotted lines Fig. 2, and I desire to claim broadly the intermediate attachment of the wire or strip —2— to the disk —1— leaving opposite free end portions adapted to form a unitary gripping part irrespective of the particular means by which such attachment is accomplished, and irrespective of whether said extractor be centrally or eccentrically attached to said disk.

The wire or strip — 2 — is provided with a pair of spurs — 5 — and — 6 —, preferably integral with and punched from the wire — 2 —, leaving the spurs united to the inner adjacent edges of the apertures and forming a continuous central portion — 7 — adapted to lie upon the upper surface of the disk — 1 — when the spurs — 5 — and — 6 — are

forced through the disk and clenched in opposite directions into contact with the lower face of said disk, and preferably, as indicated, the spurs are pressed somewhat into the lower face of the disk —1— so as to lie in a plane substantially coincident with the lower face of said disk so as not to interfere with the "stacking" of the caps, and I desire to claim, in combination with opposite free end portions adapted to form a unitary gripping handle, the specific means disclosed for attaching the intermediate portion of the wire to the disk as particularly and specifically adapted for rendering efficient and easy the removal of the cap from a bottle by the particular unitary grasping handle described.

The wire —2— preferably, as shown, extends longitudinally of a chord or base of a segment of the disk —1— and wholly to one side of the diameter of said disk parallel with said chord and traverses the radii of said segment and is attached to said disk at an eccentric point or points adjacent the periphery thereof, and I desire to claim as preferable the transverse radial, eccentric attachment of the wire, both separately and in combination with the features hereinbefore described. Preferably, the opposite end portions —3— and —4— of the wire are provided with apertures —8— and —9—, respectively, increasing the gripping efficiency of said portions, due to the fact that the flesh of the thumb or fingers of the operator will be pressed into said apertures to prevent their slipping from the handle.

In the actual operation of extracting the cap when positioned in a bottle neck, the end portions —3— and —4— are bent upwardly until their terminal portions are in substantial contact, as shown in Fig. 2, and the normal natural way of pulling upon the gripping handle is upwardly and away from the edge of the cap,—that is, an inwardly inclined substantial radial pull across the longitudinal axes of the stitches —5— and —6—, the ends of which extend in opposite directions upon the lower face of the disk, and this character of construction allows the easy removal of the adjacent edge of the disk and the gradual and easy removal of the remaining peripheral portions of the disk from the neck of the bottle without exerting any appreciable strain upon the stitches longitudinally of their axes or in a line with the stitch, but rather at substantially a right angle to the stitch, whereby the tendency to bend and release the clamping portions of the stitches from engagement with the disk is practically eliminated.

The double handle formed of the opposite end portions —3— and —4— constitutes a greatly improved gripping surface, and the uniform and simultaneous pull upon the end portions —3— and —4— exerts a uni-

form and simultaneous pull upon the stitches —5— and —6— and an equalizing tilting tendency upon the intermediate portion —7—, whereby the tendency to bend or tilt is neutralized and the possible pulling strength of the extractor greatly increased.

Although I have shown and described one particular construction, arrangement and form of the parts, I do not desire to limit myself to the same, as many changes may be made in the details of construction, arrangement and form without departing from the spirit of this invention as set forth in the appended claims.

What I claim is:—

1. A closure comprising a disk of flexible material having an elongated metal strip arranged flat face down on the top face of the disk and having a relatively short central portion secured to the disk by spurs punched from the strip and positioned on opposite sides of said central portion and passed through the disk and clenched into engagement with the lower face thereof, and opposite relatively long free end parts adapted to be bent respectively about the said central portion and having portions adapted to be brought into contact to form a unitary gripping handle.

2. A closure comprising a disk of flexible material having an elongated metal strip arranged flat face down on the top face of the disk and having a relatively short central portion secured to the disk by spurs punched from the strip and positioned on opposite sides of said central portion and passed through the disk and clenched into engagement with the lower face thereof, and opposite relatively long free end parts adapted to be bent respectively about the said central portion and having portions adapted to be brought into contact to form a unitary gripping handle, said free end parts having openings adapted to register when the said portions are in contact.

3. A closure comprising a disk of flexible material having an elongated metal strip arranged flat face down on the top face of the disk and having a relatively short central portion secured to the disk by spurs punched from the strip and positioned on opposite sides of said central portion and passed through the disk and clenched in opposite directions toward the edge of the disk and into engagement with the lower face thereof, and opposite relatively long free end parts adapted to be bent respectively about the said central portion and having portions adapted to be brought into contact to form a unitary gripping handle.

4. A closure comprising a disk of flexible material having an elongated metal strip arranged flat face down on the top face of the disk and having a relatively short central portion secured to the disk at an eccentric

point thereon and near one edge of the disk, a pair of spurs punched from the strip and positioned on opposite sides of said central portion and passed through the disk and 5 clenched into engagement with the lower face thereof, and opposite relatively long free end parts extending longitudinally of a chord of the disk and terminating adjacent the edge of the disk and adapted to be

bent respectively about the said central portion into contact with each other to form a unitary gripping handle.

In witness whereof I have hereunto set my hand this 23rd day of October, 1915.

HAROLD D. CORNWALL.
